UNITED STATES PATENT OFFICE.

HERBERT M. VINCENT, OF NEW BEDFORD, MASSACHUSETTS, ASSIGNOR TO J. C. RHODES & CO., INCORPORATED, OF NEW BEDFORD, MASSACHUSETTS, A CORPORATION OF MAINE.

ASSORTING AND DELIVERING MECHANISM.

1,261,462.

Specification of Letters Patent.

Patented Apr. 2, 1918.

Application filed July 6, 1915. Serial No. 38,331.

To all whom it may concern:

Be it known that I, HERBERT M. VINCENT, a citizen of the United States, residing at New Bedford, in the county of Bristol and 5 State of Massachusetts, have invented certain Improvements in Assorting and Delivering Mechanisms, of which the following description, in connection with the accompanying drawings, is a specification, like 10 reference characters on the drawings indicating like parts in the several figures.

This invention relates to mechanism for assorting articles, such as eyelets or eyelet blanks, from a mass contained in bulk and 15 delivering them successively in predetermined position to one or more raceways.

An object of the invention is to provide mechanism of the character indicated which shall be adapted for handling a large number 20 of articles at a high rate of speed. The invention is herein disclosed as applied to mechanism for supplying eyelet blanks to a series of raceways intended to conduct the blanks to instrumentalities which insert 25 them in strawboard sheets. This is desired in the process of producing enamel eyelets, the flanges of the eyelet blanks being coated while the blanks are inserted and held in the strawboard sheets and then the sheets with 30 the coated blanks are placed in a baking furnace. The eyelet blanks may be inserted at a high rate of speed if they can be supplied with sufficient rapidity, although heretofore they could not be supplied as rapidly 35 as they could be inserted so that the capacity of the inserting or "sticking machine" was limited by a comparatively slow rate of supply. By the mechanism herein disclosed it has been found possible for the first time to 40 insure an ample supply of blanks at a rate equal to the maximum speed of the inserting instrumentalities.

In the mechanism herein shown there is 45 provided a hopper for containing a large quantity of blanks in bulk and an inclined delivery plate to which similarly positioned blanks are supplied from the hopper and from which opens a series of raceways. This hopper is preferably relatively wide 50 with a large capacity and, as shown, the delivery plate is provided with converging walls so that the articles passing from the hopper may be concentrated in large numbers at the raceway openings.

55 The presentation of a large number of

eyelet blanks to the contracted portion of the delivery plate under certain conditions would be likely to produce a jamming or wedging of the blanks between the sides of the plate, with the result that the supply to 60 the raceways would be interrupted. I have discovered, however, that the use of a series of pins properly located with one adjacent to the opening of each raceway will prove effectual in preventing the jamming of the 65 blanks by holding back certain of them and permitting others to pass freely into the raceways.

This and other features of the invention will be best understood and appreciated 70 from the following description of a preferred embodiment thereof selected for purposes of illustration and shown in the accompanying drawings, in which,—

Figure 1 is a view in perspective with portions broken out to show certain details of construction, and

Fig. 2 is a sectional view of the mechanism shown in Fig. 1.

The hopper to which the eyelet blanks are 80 supplied in bulk comprises a large open box of substantially oblong shape having walls 10 and a bottom plate 12. The bottom plate 12 is supported at a slight inclination by a standard 14 secured to a slide plate 16. At 85 its lower edge the bottom plate 12 of the hopper merges into a delivery plate 22 which is disposed at a somewhat greater inclination than the bottom plate 12. The side walls of the delivery plate 22 converge in- 90 wardly toward the lower edge of the delivery plate and consequently concentrate into a narrower compass the eyelet blanks which pass to it from the hopper.

Extending across the upper portion of the 95 delivery plate 22, at a height sufficient to permit the passage beneath it of the eyelet blanks, is a stationary cover plate 26 having at its upper edge a flange to which is secured a separating device in the form of a toothed 100 plate or comb 24. The plate 24 is so disposed as to permit the passage from the hopper of those eyelet blanks only which rest upon their flanges.

Adjacent to the lower edge of the delivery 105 plate 22 is secured a piece 34 having a curved surface in which are formed portions of the raceways 35 which at their upper ends open from the delivery plate 22. A series of partitions comprising plates 36 are secured to 110

the delivery plate 22 between each pair of adjacent raceways. The plates 36, as shown in Fig. 1, are alternately long and short and each is curved at its upper end to meet the 5 advancing eyelet blanks.

In order to prevent the jamming of the eyelets as they approach the openings of the raceways, a series of pins 38 are set in the delivery plate 22 adjacent to the partition 10 plates 36. These pins 38 extend in two rows, from side to side of the delivery plate, between its converging walls. Each pin of the upper row of pins is located substantially opposite to the end of one of the partition 15 plates 36. Each pin of the lower row is located substantially in line with one side of one raceway. The effect of the pins is to permit the free passage to the raceway openings of those of the eyelet blanks which by 20 movement in a straight line would normally reach the openings, holding the other eyelets back temporarily and then permitting them to move laterally toward the openings. The arrangement of the pins herein disclosed is 25 not essential to the successful operation of the mechanism although it has been found in practice to be that which gives the best results. Arranged above that portion of the delivering plate 22 which carries the pins 38 30 and the partition plates 36 is a cover plate 28 connected to the stationary cover plate 26 by hinges 30. This plate may be lifted to afford access to the delivery plate for the purpose of removing an obstruction or for 35 any other purpose. A handle 40 is provided for lifting the plate 38 and a clamp 32 for maintaining it in place.

The slide plate 16 which carries all the parts above described is arranged for reciprocatory movement in guideways formed in a plate 20 which may comprise a portion of the sticking machine. The slide plate 16 is provided with an opening 18 for the reception of the upper end of an oscillating arm 45 19 secured to an operating shaft 21 as shown in Fig. 2. The vibration thus imparted to the hopper causes the eyelet blanks supplied thereto to assume by gravity their most stable position, that is to say, the position in 50 which they rest upon their flanges. As already explained, this is the position they must assume to pass through the separator cone 24 and to enter the raceways 35.

Having thus described my invention, I 55 claim as new and desire to secure by Letters Patent of the United States:

1. Assorting and delivering mechanism comprising a hopper having an inclined bottom, an inclined delivery plate leading from 60 the bottom of the hopper, a comb having spaced teeth terminating above the delivery plate, for preventing the passage of flanged

articles except in one position to the delivery plate, a raceway leading from the delivering plate, and a pin set in the delivery plate adjacent to the receiving end of the raceway. 65

2. Assorting and delivering mechanism comprising a hopper, an inclined delivery plate, a series of raceways leading from the delivery plate, and a double row of spaced 70 pins set in the delivery plate adjacent to the ends of the raceways.

3. Assorting and delivering mechanism comprising a bodily movable hopper, an inclined delivery plate, a series of raceways 75 leading from the lower edge of the delivery plate, and a row of spaced pins extending across the delivery plate above the raceway ends.

4. Assorting and delivering mechanism 80 comprising a delivery plate, means for supplying articles to the plate, a series of raceways leading from the plate, partitions with curved ends between adjacent raceways, and a pin located opposite to the end of each 85 partition.

5. Assorting and delivering mechanism comprising a delivery plate, means for supplying articles to the plate, a series of raceways opening from the plate, partitions extending upon the plate between adjacent raceways, a pin opposite to each partition, and another pin adjacent to each raceway 90 opening.

6. Assorting and delivering mechanism 95 comprising a delivery plate, means for supplying articles to the plate, a series of raceways opening from the plate, and pins set in the plate, one of which is in substantial alignment with one side of each raceway.

7. Assorting and delivering mechanism comprising a bodily movable hopper, an inclined delivery plate leading from the hopper and having convergent side walls, raceways opening from the lower edge of the 105 plate, and a row of spaced pins extending between the convergent walls above the raceway openings.

8. Assorting and delivering mechanism comprising a hopper having an inclined delivery plate with non-parallel side walls, raceways opening from the plate, pins adjacent to the raceway ends, and a removable cover plate above the delivery plate in the 110 locality of the pins.

9. Assorting and delivering mechanism comprising a hopper, a series of raceways constructed and arranged to be supplied from the hopper and alternately long and short partitions between successive adjacent 120 pairs of raceways.

In testimony whereof I have signed my name to this specification.

HERBERT M. VINCENT.
